UNITED STATES PATENT OFFICE.

RAY V. PHILLIPS, OF BROOKLYN, NEW YORK.

ELECTROMAGNETIC SIGNAL (TOY).

Application filed March 8, 1927. Serial No. 173,653.

This invention relates to improvements in electro-magnetic signals and more particularly to such signals for use on toy railroads, and the like.

5 An object of the present invention is to simplify and cheapen the construction of such devices, so as to place the same within reach of the general public.

Heretofore, it has been the practice of toy manufacturers, particularly those interested in the production and sale of electrical toys, such as railways and their accompanying accessories, to utilize structures of more or less complication which necessarily increased 15 the sale price to such an extent as to render the sale of the articles practically prohibited to the man of ordinary means.

It is, therefore, another object of the invention to reduce the cost of manufacture, 20 yet retain the essential elements of the articles so as to popularize and increase the utility of accessories of the nature above described.

A feature of the present invention is the 25 unitary structure of the device which adapts it for use equally as well in the operation of gates or semaphores, so that no alteration by the manufacturer is required to adapt the electrical unit for operating either type 30 of accessory.

Another feature of the invention is the unitary structure of the electro-magnet enclosing shell with the standard for supporting the signal so that the fewest possible 35 number of parts are involved and the least amount of handling required to assemble the entire device.

With the above and other objects in view, the invention consists in the novel construction, combination, and arrangement of parts, 40 which will be fully set forth in the following specification, claimed and illustrated in the accompanying drawing in which:

Figure 1 is a top plan view of a toy railway gate equipped with this improved unit,

Figure 2 is a side view thereof showing portions in section to more clearly illustrate the details of construction,

Figure 3 is a transverse sectional view 50 taken on line 3—3 of Figure 2,

Figure 4 is a top plan view of the unit applied to a toy semaphore, and

Figure 5 is a side view of Figure 4 show-

ing portions broken away so as to more clearly illustrate the details of construction. 55

Referring to the drawings in detail, the solenoid core constituting a tubular body 10 of insulating material is provided at one end with a cylindrical extension 11. Secured to the core adjacent opposite ends are heads 12 60 of insulating material, and wound on said core between the heads is a winding 13 of an electrical conductor, the layers of which are insulated over each other, as is common practice. The terminals of the conductor 65 extend outward through one of the heads 12 and are carried to binding posts mounted on a suitable base, which will be more fully hereinafter described. Surrounding the winding 13 is a tubular metallic shell 14 70 formed from a metal sheet provided with flange extensions 15 which lie next to each other when the sheet is bent into cylindrical form to provide a standard on which the signal is pivotally mounted. Tongues 16 75 are formed on one of the flanges 15, and as illustrated in Figures 2 and 3 are bent over the opposite flange to hold the parts in assembled position and thereby form a complete standard. The upper ends of the 80 flanges project above the body of the cylinder 14 and are pierced to receive a pivot pin 17 upon which signal is pivotally supported.

The signal 18, which in Figures 1 and 2 is illustrative of the customary railway crossing gate, comprises an arm 19, pierced 85 to receive the pivot pin 17 and provided with an opening to receive the pivot pin 20 of the movable solenoid armature 21, the opposite end of which is disposed within the 90 tubular core 10, so that when the coil 13 is energized the armature 21 will be drawn into the core 10, as indicated in the dotted line positions of Figures 1 and 5. In order to limit the movement of the arm 19 toward the coil 13, a stop 22 is formed on one edge thereof and engages against the armature 21 when the arm has reached its full limit of movement in one direction. Movement in the opposite direction is limited by engagement of one wall of the notch 23 against the tongue 24 formed above the upper edge of the tubular shell on one of the flanges 15 which serves to bind the flanges together 95 near the pivot 17.

In the gate structure illustrated in Fig-

ure 1, the arm 19 is projected as at 25 past the pivot 17 and counterweighted as at 26, so as to normally hold the blade 27 in elevated position.

5 In the structure shown in Figures 4 and 5, the arm 19 projects past the pivot 17 to provide a semaphore blade 28 which is of sufficient weight to overcome the weight of the opposite end and the armature 21, so as 10 to normally hold the blade in the dotted line position shown in Figure 5. It will be noted that in Figures 4 and 5, the arm 19 terminates in the stop 22, and a similar extension 29 which are preferably painted 15 or printed to represent signal lamps.

When the device is used in connection with the gate, such as illustrated in Figures 1 and 2, the cylindrical extension 11 is entered into, a suitable base 30 carrying binding posts 31 to which terminals of the winding 13 are connected. While the frictional contact between the cylindrical extension 11 and the wall of the opening into which it extends is ordinarily sufficient to retain the 25 device in proper position on the base, it may be found desirable to form the shell 14 and the lower end of the flanges 15 with outwardly extending ears 32 and 33 respectively, which may be secured to the base in the 30 manner illustrated. Such ears are not an absolute essential, but are provided to insure stability.

In the structure illustrated in Figures 4 and 5, the cylindrical extension 11 projects 35 into the upper end of tubular column 34 which may in turn be supported in any suitable manner and the terminals of the coil 13 conveyed through the column as illustrated to suitable binding posts (not 40 shown). From the foregoing, it will be apparent that a unit is provided which is capable of practical universal application wherever an electro-magnetically operated apparatus or mechanism is employed which 45 is particularly adapted for electrical toys and the same unit equally applicable to the operation of crossing gate as to a semaphore signal. This unit may be easily and cheaply constructed and readily assembled at a minimum of labor and expense, so that a toy 50 manufacturer may readily adapt the device for the production of many and varied accessories.

55 While in the foregoing there has been shown and described the preferred embodiment of this invention, it is to be understood that minor changes in the details and construction, combination and arrangement of parts, may be resorted to without departing from the spirit and scope of the invention as claimed.

What is claimed is:—

1. As a new article of manufacture, an electro-magnetic control unit for signals,

comprising a magnet winding, supporting 65 means therefor, a sheet of material bent to form a cylinder embracing the winding and having engaged flanges on one side of the cylinder extending radially therefrom, and extensions on the flanges projecting be- 70 yond one end of the cylinder, said flange extensions forming a standard in fixed definite relation to the longitudinal axis of the magnet winding.

2. A new article of manufacture comprising 75 a tubular core having means at one end for connection to a base, a magnet winding supported on said core, a cylinder enclosing the winding and having radially extending opposed flanges and tongues on one of the 80 flanges overlying the other flange to bind the same together and form a standard, said standard projecting beyond the end of the cylinder.

3. An electro-magnetic operating unit for 85 signals comprising a magnet coil, a sheet metal band enclosing said coil and having its end portions radially extended to form 90 flanges constituting a supporting standard for a movable signal member, and one of said flanges having parts engaged with the other flange to secure said flanges upon each other and retain said band in close encircling engagement upon said coil.

4. As a new article of manufacture, an 95 electro-magnetic operating unit for signals comprising a base, a tubular core, a winding 100 on said core, a sheet metal band enclosing said winding and having its end portions ex- 105 tended radially to form flanges, each of said flanges having a longitudinally extending portion projecting above the upper end of said core, means for securing said flanges in contact with each other and contracting said band closely upon said winding, means for 110 rigidly fixing each of said flanges at its lower end to the base, said flange extensions constituting supporting means for a movable signal member, and an armature movable within said core.

5. In combination, an electro-magnetic operating unit including a coil, a cylinder embracing and holding said coil and having a flange extension projecting longitudinally beyond one end of said cylinder to constitute 115 a supporting standard, an arm pivotally mounted on said standard and counterbalanced to normal position in obliquely inclined relation to said standard, and an armature associated with said magnet coil 120 and connected with said arm to move the latter from its normal position upon energization of the coil.

6. In combination, an electro-magnetic operating unit including a coil, a cylinder of 125 sheet material embracing and holding said coil, the ends of the sheet being laterally ex- 130 tended to form flanges, and said flanges pro-

jecting longitudinally beyond one end of the coil to constitute a supporting standard, means for securing said flanges to each other, an arm pivotally mounted between and upon 5 the ends of said flanges and counterbalanced to a normal position in obliquely inclined relation to said standard, and an electro- magnet armature associated with said coil and connected with the arm to move the latter from its normal position upon energization of the coil.

In testimony that I claim the foregoing as my invention, I have signed my name hereto.

RAY V. PHILLIPS.
